COSMETICS MATCHING MIRROR

Robert C. Dorr, Woodland Hills, Calif., assignor to Ameritone Paint Corporation, Compton, Calif.

Filed June 24, 1974, Ser. No. 482,132

Term of patent 14 years

Int. Cl. D28—03

U.S. Cl. D86—10 H

Fig. 2

Fig. 1

FIG. 1 is a front elevational view of the cosmetics matching mirror showing my new design; and

FIG. 2 is an end elevational view.

The back is plain and unornamented.

I claim:

The ornamental design for a cosmetics matching mirror, substantially as shown and described.
